BASKET AND COVER CONSTRUCTION

George E. Bomberger, Indianapolis, Ind., assignor to Fruit and Produce Packing, Inc., Indianapolis, Ind., a corporation

Application July 25, 1935, Serial No. 33,097

11 Claims. (Cl. 229—52)

This invention relates to baskets.

The chief object of this invention is to reduce the cost of basket structures.

The simplification consists in forming the body of the basket of corrugated paper board stock or stock of an equal character and peripherally with but single width thickness of side and end walls and bottom, except for overlapping flaps and associating therewith a handle in an improved manner. The double wall structure of previous baskets for handle anchorage is thereby eliminated. The additional fabrication required by such a double wall basket in setting up is eliminated. The additional material required for such double wall structure is also eliminated. The result is a dual saving.

This permits the fabrication of relatively small capacity baskets at a lower unit price which increases its range of commercial acceptability having reference to the contents to be placed therein; as for example, a basket of approximately the volume of an ordinary shoe box or four quarts can be provided at a completed cost sufficiently low to permit the basket sale of tomatoes packed therein at but a few cents per pound.

Also, single thickness board readily lends itself to printing which improves the appearance of the pack.

Another object of the invention is to provide ventilation when desired, through the walls to the contents and this is readily possible when a single width side wall arrangement is utilized.

The chief feature of the invention consists in suitably deforming or recessing a splittable single width wall so that the end of the handle may be received thereby and be nested in the wall and suitably secured thereto, thus leaving a finished and/or printed outside wall surface and a relatively finished inside wall surface, the former offering no obstruction to handling and the latter insuring non-marring or non-bruising of the articles, such as tomatoes, apples, or like contents in the basket.

A subsidiary feature of the invention consists in providing a locating arrangement so that the degree of handle nesting may be accurately determined.

Another feature of the invention consists in providing a cover for the basket which is yieldingly locked to the same by notches, the cover resting on the top edge of the sides and ends and said cover having a scoring, the cover being formed of corrugated paper board, or the like, the scoring extending from one side to the opposite side and lying parallel to the corrugations.

Thus, either end of the cover may be readily tilted for inspection or removal of the contents of the basket without exposing the contents at the other end.

The full nature of the invention will be understood from the accompanying drawing and the following description and claims:

In the drawing, Fig. 1 is a perspective view of a basket embodying one form of the invention.

Fig. 2 is a top plan of a cover for the basket, the overall dimensions being preferably greater than the interior overall dimensions of the box portion of the basket shown in Fig. 1 but not appreciably greater than the exterior overall dimensions thereof.

Fig. 3 is an end elevation of the cover shown in Fig. 2. The dotted lines in Fig. 2 indicate a multiple hinge scoring arrangement, while the dot and dash lines in the same figure indicate a single hinge arrangement. These are in elevation in Fig. 3.

Fig. 4 is a plan view of the blank from which the basket box formation is fabricated.

Fig. 5 is a broken-away elevational view of the inside of the container adjacent the handle anchorage.

Fig. 6 is a view similar to Fig. 5 of a modified form of handle anchorage.

Fig. 7 is a view similar to Figs. 5 and 6 and of a modified form of handle anchorage.

Fig. 8 is a sectional view taken at right-angles to Fig. 7.

In Figs. 1 and 4 of the drawing, 10 indicates the bottom portion of a single sheet of double face corrugated board. 11 indicates the side wall forming portions integral therewith and hingedly connected by the scorings 12. Portions 13 constitute end-forming extensions integral with and hingedly connected as at 14 to the bottom 10.

In the present form of the invention, there is hingedly connected as at 16 at opposite ends of the side wall portions 11, flaps or end reinforcing extensions 15 which are separated from the end portions proper by the slit or cut 17. These several portions are arranged in open box formation, as shown in Fig. 1, with the portions 15 in the present form of the invention, lying within the portion 13 and suitably secured thereto as by the clips 18. Portions 15 may lie exteriorly of the box or may be integral with the end walls 13.

The resultant structure, as stated, is an open box formation having single width side walls 11.

The board includes, so far as the side wall is concerned, an outside liner 19, an intermediate corrugated portion 20 and an inside liner 21. The direction of the corrugations, as shown in Figs. 1 and 5, is longitudinal, or from end to end of the box in preference to positioning in the opposite direction for the reason which will appear more fully hereinafter.

Intermediate the ends of the single width basket wall and between the two liners, there is formed a recess 22 by the use of a stabbing tool, or the like, which crowds the corrugated portion 20 originally positioned in the area of the recess into the unoccupied space of the corrugated portion, as indicated at 23, thereby forming a fairly rigid wall, thus forming a fairly rigid socket with the liners 19 and 21.

A flexible handle of ply-wood, or the like, 24 has the two ends 25, each of which is adapted to be nested in or received by the socket or recess. The handle may carry a designating legend 26 to determine the exact depth of insertion, such designation registering with the top edge 27 of the side wall, if desired, or if this form of measurement is not desired, an aperture 28 may be formed in the wall and in longitudinal alignment with the socket or recess 22. The end 25 of the handle when exposed by the recess 28 determines the amount of nesting.

A clip 30 or a pair of clips, if desired, may extend through both liners and the handle and thus rigidly secure the handle end to the recessed wall and in nested relation. The socket thus formed, as previously stated, constitutes a resistance to handle tilting and usually only a single clip 30 is necessary for handle end anchorage or no clips may be used as hereinafter set forth. Also, if desired, the nestable ends of the handles may be dipped in an adhesive before insertion into the wall recesses. This eliminates stitching or stapling for light load capacities.

The question may be raised as to why the handle end might not be stapled or clipped to the exterior or to the interior of the supporting wall. It is well recognized in this art that positioning the handle on the outside of the supporting wall constitutes an obstruction which in the handling of the baskets, invariably tears the handle from the supporting wall.

Positioning of the handle exteriorly also interferes with any complete face printed design. Therefore, the handle should not project beyond the exterior plane of the supporting wall. This leaves only two positions to remain—one of which is to position it on the inside of the supporting wall and thus project inwardly into the box portion of the basket beyond the plane of the inside of the supporting wall. Such handle anchorage forms an obstruction or projection in the box which in the handling of the articles, such as apples, grapes, tomatoes, peaches, plums, and the like, will result in marring and bruising of the fruit in the basket, and reduces the cubic volume which the United States Bureau of Standards might not tolerate.

Positioning of the handle either exteriorly or interiorly as will be evident, requires dual or spaced anchorage to prevent handle tilting.

Heretofore, it has been well recognized in the art the handle anchorage must not project beyond the exterior plane of the supporting wall or inwardly beyond the interior plane of the supporting wall.

This protective type anchorage heretofore in the art has been accomplished by making the

supporting wall of double width formation by providing a second wall portion which may be positioned interiorly or exteriorly with reference to the main wall and the extra wall portion may constitute an inner or outer extension of the main wall. The handle in such a case extends through an opening formed at the hinge joint of the supporting wall and it is extended and is nested between the overlapped walls and is clipped to the same. However, there is nothing to prevent rocking of the handle from the time it is positioned in the opening until the time it is stapled or clipped so that there is no guarantee the handle will be anchored accurately in predetermined position. This type of structure requires no additional board stock, as is self-evident, but an additional tilt-preventing staple in each leg of the handle.

The present invention, therefore, has every advantage of a double side wall structure and none of its disadvantages and several additional advantages of its own, which have been herein-before referred to.

If desired, the several walls may have semi-perforated or preformed openings 40 provided there-in which may be readily removed by punching with the finger, pencil, or the like, the portion 41 from the main body or stock. It is to be understood the blanks shown in Fig. 4 and the handle shown in Fig. 1 are shipped in bulk and in knock-down condition, and are fabricated by the fruit or vegetable packer with a stapling or stitching machine, as it is called. In Fig. 6 of the drawing, there is illustrated a modified form of handle anchorage and similar numerals of the one hundred series are applied to similar or identical parts as are found in Fig. 5. Thus, 124 indicates the handle leg, 126 the legending that is operatively associated with the top edge 127 of the supporting wall having the inner liner 121, the outer liner 119 and the intermediate corrugated portion 120. Also illustrated is the bottom 110.

A stabbing tool has formed the recess 122 in the single width side wall between the liners and has deformed the corrugated material into the spacing and thus forms a rigid wall recess with liners 119 and 121 by reason of the material 123 crowding into the spacing in the corrugated portion 120.

In this form of the invention, however, the handle 124 on opposite sides is provided with serrations 130 which permit the handle end to be readily forced into the recess to the desired depth and when once nested therein for automatic lock in the recess. With this form of the invention no staples are required, although as an added protection or method of anchorage preferably adhesive could be applied to the barbed or serrated end of the handle so that after once inserted, the handle rigidly would be secured in the recess.

Figs. 7 and 8 illustrate a still further modified form of the invention. In this form of the invention similar numerals of the two hundred series are employed. The bottom 210 has integral with it the side wall provided with an inside liner 221, an outside liner 219 and the intermediate corrugated portion 220. A recess 222 is provided between the two liners and the material of the corrugations deformed by the stabbing tool is forced as at 223 into wall formation to form a recess or pocket.

In this form of the invention, the handle 224 may be provided with the indicating legending 75

226 cooperating with the upper edge of the wall 227.

The handle may, if desired, be provided with the serrated edges 230 for barbed or interlocking relationship with the portions 223 of the wall of the recess.

The extension feature of this form of the invention, which is herein shown associated with the barbed portion of the handle which may independently be employed without the same, is a lateral extension 261 on the end of the handle or adjacent its lower edge which is nestable in a recess 260 in the liner 221 as shown, or in a similar recess in the outer liner 219 or the handle end 15 may have oppositely directed portions 261 nestable in aligned recesses in both liners.

If desired, a plurality of said barbs 261 may be provided for multiple association with a plurality of superposed recesses or openings 260 in the inside, outside or both liners. In this form of the invention, if desired, adhesive may be employed with the barbed end of the handle, or if desired, no adhesive need be applied.

It is customary to provide baskets of this general character with covers which have an area greater than the interior area of the basket at its upper edge and approximately of the or but slightly greater area than the exterior area of the top edge of the basket so the cover rests upon the upper edge of the basket and particularly the box portion thereof.

Figs. 2 and 3 illustrate in plan and side elevation, a cover of corrugated board stock. The upper liner is indicated by the numeral 50, the lower by the numeral 51 and the intermediate corrugated portion by the numeral 52. The direction of the corrugations is shown clearly in the broken away portion in Fig. 2. The cover is notched as at 53 at opposite sides to nest about three sides of each handle end as it emerges from the side wall of the box.

In one form of the invention, as shown by the dot and dash lines, a single score or hinge connection is provided, indicated by the numeral 54 and the same is parallel to the handle and the longitudinal direction of the corrugations. This hinge arrangement permits either end of the cover to be tilted relative to the other for exposing the contents of the basket for removal or inspection.

As is customary in grape and peach baskets, they are frequently stacked in pairs, the baskets in successive pairs being transversely positioned relative to the next lower pair of baskets. Of course, it is understood the height of the handle above the top edge of the basket or more particularly above the upper plane of the cover is usually equal to or less than the over-all height of the box formation. Having the corrugations in the cover extending parallel to the handle, insures greater rigidity in the cover which serves as a base for the superposed basket so if the basket is slightly offset and not in exact registration, the cover has sufficient strength by reason of the positioning of the corrugations, so it can support without buckling or bending, the superposed baskets in the tier.

A modified form of the invention is illustrated by the dotted lines 55. These, as shown clearly in Fig. 2, are parallel to each other and offset slightly from the notched portions 53 and are parallel to the handle. This insures the cover may be more or less permanently associated with the basket and in this form of the invention, if desired, and as shown in Figs. 2 and 3, as at 56, the surplus may

extend upwardly and be stapled to the handle. If it is not stapled to the handle, it constitutes an additional interlocking arrangement for yieldingly retaining the cover on the basket and preventing accidental dislodgement or disengagement 5 therefrom. Of course, if the median hinge arrangement is utilized, the upstanding portions 56 preferably are omitted. To insert cover, press downward on assembled handle at top of bow, thus forcing side walls 11 outwardly and increasing 10 the distance between the handle legs, so that the lid may be inserted freely, and it is locked in place when handle pressure is released.

Baskets of this general character are approximately of shoe box size and will hold four quarts. 15 With the handle structure not projecting from the inside of the side wall, the volume of the basket is accurate and fully complies with the rules and regulations of the Weights and Measures Division, Department of the Government. 20

Furthermore, it is to be understood the invention is not necessarily confined to corrugated board but may be applied to any splittable paper board stock, unless the claims specifically recite the same, although it is to be understood that 25 unless the claims specifically refer to a relationship with the direction of corrugating, the term "corrugated" is intended to cover an indented or embossed intermediate portion of stock as well.

While the invention has been described in great 30 detail in the foregoing description, the same is to be considered as illustrative and not restrictive in character. Various modifications have been illustrated and described and these as well as others which will readily suggest themselves to persons 35 skilled in this art, all are considered to be within the scope of this invention, reference being had to the appended claims.

The invention claimed is:—

1. A basket of paper board stock and comprising a bottom, side walls and end walls secured together in box formation, the walls being of single width thickness with an exterior liner and an interior liner and an intermediate portion, the latter being deformable to form a handle recess in 45 the handle-supporting wall between the liners without appreciably increasing the width of the wall when a handle end is nested therein, and a handle for the basket.

2. A basket of paper board stock and comprising a bottom, side walls and end walls secured together in box formation, the walls being of single width thickness with an exterior liner and an interior liner and an intermediate portion, the latter being deformable to form a handle recess in the 55 handle-supporting wall between the liners without appreciably increasing the width of the wall when a handle end is nested therein, a handle for the basket, and a cooperative connection between the supporting wall and the handle for handle anchorage.

3. A basket of paper board stock and comprising a bottom, side walls and end walls secured together in open box formation, the walls being of single width thickness with an exterior liner and 65 an interior liner and an intermediate portion, the latter being deformable to form a handle recess in the handle-supporting wall between the liners without appreciably increasing the width of the wall when a handle end is nested therein, a handle 70 for the basket, and handle-indicating means determining the depth of handle insertion in the recess.

4. A basket of paper board stock and comprising a bottom, side walls and end walls secured to 75

- gether in open box formation, the walls being of single width thickness with an exterior liner and an interior liner and an intermediate portion, the latter being deformable to form a handle recess in the handle supporting wall between the liners without appreciably increasing the width of the wall when a handle end is nested therein, a handle for the basket, and barb means on the nested handle end for handle anchorage.
10. 5. A basket of paper board stock and comprising a bottom, side walls and end walls secured together in open box formation, the walls being of single width thickness with an exterior liner and an interior liner and an intermediate portion, the latter being deformable to form a handle recess in the handle supporting wall between the liners without appreciably increasing the width of the wall when a handle end is nested therein, and a handle for the basket, said handle and an edge portion of the box cooperating for determining the depth of recess insertion of said handle, said box edge being that of an aperture in the inner liner of the wall adjacent the bottom and in alignment with the recess.
15. 6. A basket of paper board stock and comprising a bottom, side walls and end walls secured together in open box formation, the walls being of single width thickness with an exterior liner and an interior liner and an intermediate portion, the latter being deformable to form a handle recess in the handle supporting wall between the liners without appreciably increasing the width of the wall when a handle end is nested therein, and a handle for the basket, said handle and an edge portion of the box cooperating for determining the depth of recess insertion of said handle, said box edge being that of an aperture in the side wall adjacent the bottom and in alignment with the recess, and barb means on the handle for handle anchorage.
20. 7. A basket of paper board stock and comprising a bottom, side walls and end walls secured together in open box formation, a pair of opposite wall portions thereof each being vertically recessed from the top edge toward the bottom, a handle, the opposite ends thereof being nestable in the vertical recesses, and means securing the handle ends to the recessed walls, the vertical side walls of each recess preventing tilting of the handle end and locating the same prior to anchorage.
25. 8. A basket of splittable paper board stock and comprising a bottom, side walls and end walls secured together in open box formation, the walls being of single width thickness, each handle-

supporting wall at its midportion being split from its upper edge toward the bottom, a handle end seatable in the split, and a cooperating connection between the supporting wall and handle end for securing the same together.

5

9. A basket of paper board stock and comprising a bottom, side walls and end walls secured together in box formation, the walls being of single width thickness with an exterior liner and an interior liner and an intermediate portion, the latter being deformable to form a handle recess in the handle-supporting wall between the liners without appreciably increasing the width of the wall when a handle end is nested therein, a handle for the basket, and a cooperative connection between the supporting wall and the handle for handle anchorage, the supporting wall intermediate portion being of "corrugated" character, the recess-forming deformed portion thereof being crowded into spacing between the liners and the adjacent "corrugated" portion to form a relatively rigid continuously walled recess with the liners to accurately and relatively fixedly locate the handle end.

10

10. A basket of paper board stock and comprising a bottom, side walls and end walls secured together in open box formation, the walls being of single width thickness with an exterior liner and an interior liner and an intermediate portion, the latter being deformable to form a handle recess in the handle-supporting wall between the liners without appreciably increasing the width of the wall when a handle end is nested therein, a handle for the basket, and handle-indicating means determining the depth of handle insertion in the recess, said handle-indicating means including a mark on the handle cooperating with an upper edge of the basket side wall.

25

11. A basket of paper board stock and comprising a bottom, side walls and end walls secured together in open box formation, the walls being of single width thickness with an exterior liner and an interior liner and an intermediate portion, the latter being deformable to form a handle recess in the handle-supporting wall between the liners without appreciably increasing the width of the wall when a handle end is nested therein, a handle for the basket, and handle-indicating means determining the depth of handle insertion in the recess, said handle-associated side wall near the bottom thereof having a recess therein for exposing the end of the handle, and the said handle-indicating means thereon comprising the end of the handle.
